UNITED STATES PATENT OFFICE.

THOMAS FRANK GREGORY, OF HENNING, TENNESSEE.

WHIFFLETREE.

1,020,196.

Specification of Letters Patent.

Patented Mar. 12, 1912.

Application filed November 29, 1911. Serial No. 663,108.

To all whom it may concern:

Be it known that I, THOMAS F. GREGORY, a citizen of the United States, residing at Henning, in the county of Lauderdale and 5 State of Tennessee, have invented a new and useful Whiffletree, of which the following is a specification.

This invention relates to improvements in whiffletrees, while it may be adapted for 10 other utilities, as for instance, a neck or breast yoke and the like.

The invention has for its object to provide for bracing the device against a pulling strain or other stress.

15 A further object is to provide for securing the trace against possible casual detachment from the whiffletree, especially when the pulling action is relaxed and the whiffletree assumes a dependable position.

20 A still further object is to carry out the aforesaid ends in a simple, inexpensive and effective manner.

The invention consists of certain instrumentalities and features substantially as 25 hereinafter fully disclosed and defined by the claim.

In the accompanying drawing illustrating the preferred embodiment of my invention wherein it will be understood that various 30 changes and modifications may be made as relate to the detailed construction and arrangement of the parts without departing from the spirit thereof, Figure 1 is a perspective of the invention, one of the trace-hooks or fastenings, however, being omitted. Fig. 2 is a plan view of the same complete. Fig. 3 is a section taken on the line $x-x$ of Fig. 1. Fig. 4 is a section taken on the line $y-y$ of Fig. 1. Fig. 5 is a detached perspective of a bracket-like brace between the trace-hook ended member and the slidable bar or brace.

In carrying out my invention, I provide a combined trace-hook-ended and whiffletree 45 attaching member 1, which is preferably formed from suitably conformed rod-metal, said rod-metal member being provided with or twisted into a central attaching loop or eye 2. The end portions of said rod-metal member are extended or directed at right-

angles or laterally to the general trend of the body-portion thereof, as at 3, said right-angled or lateral portions or extensions 3 terminating in trace-attaching loops or fastenings 4, themselves formed with recurved 55 terminals 5 for aiding the retaining action thereof, as will be readily appreciated. A stretcher or brace 6, preferably of wood although it may be of metal, spans the interval between, and is suitably applied to the 60 right-angled or lateral extensions or portions 3 of the member 1, connection therebetween being effected preferably by means of metal-loop or eye forming members or keepers 7 suitably fixed or secured to said 65 stretcher or brace 6 at its ends and receiving said lateral or right-angled portions or extensions of said member 1. The keepers or eye-members 7 afford such connection between the brace or stretcher 6 and member 70 1 as to preclude any yielding or binding action therebetween, and said keepers or eye-members are adapted to so receive the lateral portions 3 of the member 1 as to allow of a sliding action or movement of said member 75 6 thereon, whereby, it is apparent that as the pulling action or strain upon the traces and accordingly upon the whiffletree is relaxed, the latter will drop into a dependable position, which will allow the member or 80 stretcher 1, thus rendered slidable, to engage by gravity the backs or bends of the recurved portions 5 of the trace-hooks or loops 4, and thus prevent the casual detachment of the traces therefrom, which would otherwise occur by reason of the resultant slack in the traces, as will be readily appreciated.

A bracket-like member 8 is suitably secured to the member 6, about centrally of its rear edge and is adapted to brace the 90 member 1 intermediate of its ends, as shown.

It is apparent that by exchanging for the trace-forming hooks 4 rings and employing rings in connection with the eye 2, the device may be used for certain other utilities, as 95 a neck or breast yoke or analogous contrivance.

What is claimed is:

A whiffletree, including a stretching bar, an attaching member having lateral exten- 100

sions terminating in trace-engaging hooks, themselves having recurved terminals, and means providing for slidable connection between said stretching bar and said lateral extensions, for the engagement of said stretching bar with the bends or backs of said trace-forming hooks.

In testimony that I claim the foregoing as my own, I have hereto affixed my signature in the presence of two witnesses.

THOMAS FRANK GREGORY.
